UNITED STATES PATENT OFFICE.

NATHANIEL C. STAMPS, OF LOS ANGELES, CALIFORNIA.

CARBURETER.

1,140,721.

Specification of Letters Patent. Patented May 25, 1915.

Application filed August 7, 1911. Serial No. 642,781.

To all whom it may concern:

Be it known that I, NATHANIEL C. STAMPS, a citizen of the United States, residing at Los Angeles, in the county of Los Angeles and State of California, have invented new and useful Improvements in Carbureters, of which the following is a specification.

This invention relates to improvements in carbureters and particularly such as are useful in connection with automobile explosive engines.

It is an object of the invention to provide a carbureter for explosive engines in which the gasolene and air feed as well as the throttle mechanism are under a positive control for delivering proper quantities of the materials composing the explosive mixture to the engine.

It is also an object of the invention to provide a carbureter with a gasolene feed which may be set for low speed operations of the engine and to provide an air controlling inlet mechanism which when operated to deliver larger quantities of air to the throttle device of the engine, will also increase the gasolene supply to a proportionate extent.

It is also a further object of the invention to provide a carbureter with positively controlled gasolene and air feed mechanism and with means for adjusting each.

In the accompanying drawing forming a part of this specification, Figure 1 is a vertical central sectional view through a carbureter constructed in accordance with the present invention, a small portion of the casing being shown in side elevation to illustrate the co-operative adjusting features of the device. Fig. 2 is a fragmentary sectional view taken upon the line 2—2 of Fig. 1 and showing the air feeding mechanism and the throttle casing in elevation 1. Fig. 3 is a horizontal sectional view taken upon the line 3—3 of Fig. 1. Fig. 4 is a detail fragmentary view of one of the ball connections interposed between the throttle mechanism and the air controlling device.

The details of the invention will now be more specifically described reference being had to the drawing in which 10 indicates a casing having a passage-way 11 formed through the same, which is open at one end

to the atmosphere while the other end leads into the mixing chamber of the device. The passage 11 is preferably considerably depressed at a point intermediate its length to 55 form what may be termed a goose neck passage as at 12, a partition wall 11^a projecting downwardly into the same from the top wall of the casing, to a point near the bottom of said passage. Projecting downwardly from 60 the casing at the bottom of said goose neck passage is a hollow stem 13 which is provided with a longitudinally extending bore 14 closed at the bottom by a plug 15. The said bore 14 connects with a transverse passage 16 which opens into the float chamber 17 of the carbureter device. The upper end of the bore 14 is formed with a valve seat 18 which is controlled by a valve 19. The valve 19 is preferably a pin valve which engages 65 an elongated bearing 20 in the partition wall 11^a, the upper end of said valve passing out through a plug 21 which closes an enlarged space 22 formed about the upper end of said pin valve. A spring 23 located in said 70 space 22 bears against the said plug 21 at its upper end and at its lower end against a collar 24 secured to the said pin valve 19. The spring 23 thus tends to force the valve to its seat at the upper end of the gasolene inlet or 75 bore 14.

The extreme upper end of the pin valve 19 is threaded and engages an adjustably threaded clamp 25 which is carried by a transverse bar 26. The milled head 27 is provided at 80 the upper end of the pin valve 19 so that by turning the said valve it may be adjusted to different heights in the clamp 25. A set screw 28 is employed for tightening the clamp 25 after the said pin valve 19 has been 85 adjusted. The outer end of the bar 26 is provided with an antifriction roller 29 which movably engages parallel standards 30 rising from the casing 10 to one side of the valve 19. The bar 26 may thus rise and 90 fall between the said standards 30 and yet 95 cannot swing about the axis of the valve 19.

The inner end of the bar 26 is provided with an anti-friction roller 31 which bears 100 on an adjacent part carried by the air controlling mechanism as will be hereinafter described, whereby the valve 19 controlling

the inlet of gasolene or other hydro-carbon materials will be adjusted or raised and lowered in accordance with the supply of air to the mechanism.

5 The construction of the goose neck is such that the gasolene which is fed to the carbureting chamber formed by the goose neck through the bore 14 when the valve 19 is slightly raised will be taken up by the air drawn through the said goose neck and carried therefrom through an opening 32. The said opening 32 is formed at the bottom of a depressed wall 33 of the casing 10, which forms the bottom of the air inlet and mixing 10 chamber of the device. The surface of said depressed wall 33 is somewhat cup shaped converging toward the opening 32 so that any condensation of hydrocarbon vapors passing into the mixing chamber that might 15 possibly collect therein will be directed back into the air passage and either be taken up afresh or run back into the inlet bore 14. In the event of the valve 19 being seated and the collecting of the gasolene in the bottom 20 of the goose neck for any unusual cause or reason, it may overflow through a pipe 34, set at the upper end of a drain passage 35 which passes out through the stem 13. In this manner the clogging or flooding of the 25 device is guarded against.

The float chamber 13 is formed in a casing 36 which forms a lower extension of the casing 10 and surrounds the stem 13. A float 37 of any ordinary type is mounted in said 30 float chamber surrounding the stem 13 and engages a forked lever 38 which is pivoted at 39 in an extension frame upon said casing 36. An inlet valve 40 is movably mounted in said 35 casing extension and is adapted to control a gasolene inlet 41. The valve may be of any ordinary type and the supply pipe for feeding the gasolene or other hydro-carbon materials is connected by a nipple 42 with the extension casing so as to admit the gasolene thereto under the control of the said 40 valve 40. It will be evident that any suitable float controlled valve mechanism, may be employed for admitting the gasolene to the float chamber.

45 Mounted upon the casing 10 and over the cup shaped depressed wall 33 is a casing 43 having a series of ports 44 formed in its walls. There are preferably a plurality of such ports arranged at different points 50 around the circumference of the casing so that the air entering the said casing will rush in toward the center from all sides. Movable mounted outside the casing 34 is a controlling sleeve 45 which is provided 55 with a number of openings 46, the said openings corresponding in number and size to the ports 44. The structure is such that when the sleeve is moved in one direction the opening 46 may be brought into coincidence with the ports 44 for admitting sec-

ondary air to the full capacity of said ports. By moving the sleeve in the other direction the openings at the ports may be gradually reduced or entirely cut off as found desirable.

70 The sleeve 45 is provided with a flange 47 near its upper edge from which projects an arm 48 by which the said slide is turned. At a point under the bar 26, the said flange 47 carries an adjustable spring cam 49. The cam 49 is secured at one end to the flange 47 by means of screws or rivets 50 and at a point intermediate its length the said cam is bent upwardly in an inclined manner, the free end of said cam resting upon an adjusting screw 51 carried by the said flange 47. The incline of the cam 49 is such that as the sleeve 45 is turned to introduce larger quantities of air as in speeding up the engine, the roller 31 which extends over the 75 said cam so as to rest upon the same, will be correspondingly lifted so as to raise the valve 19 and increase the flow of gasolene or other hydro-carbon material into the carbureting chamber in the goose neck. The 80 cam 49 is readily bent to give it exactly the right incline when the instrument is first made and adjusted, and any slight alterations necessary therein can thereafter be made by adjusting the screw 51. It will be seen 85 that the carbureter thus has two adjustments. First the valve 19 is adjusted by turning the milled head 27 so as to feed the quantity of gasolene necessary for the lowest speed of the engine. The cam 49 is then 90 adjusted for the high speeds of the engine, for until high speeds are to be employed it is not necessary to open the ports 44.

95 Mounted upon the upper edge of the casing 43 is an upper casing 52 which is reduced at its upper end to form a passage 53 to receive the usual throttle valve 54. The 100 said throttle valve is preferably a circular plate carried by a transversely extending shaft 55 having bearings at its ends in the 105 walls of the casing 52. The shaft also extends beyond the said bearings and one end has secured to it an operating lever 56 of usual construction, while the other end carries an arm 57 which is connected by means 110 of a link 58 with the arm 48 of the sleeve 45. The connection of the said link 58 with the arm 57 and also the arm 48 is approximately of the universal type, so that the said link 58 may accommodate itself to 115 the various movements of the two parts which operate in different planes. Thus a 120 stud 59 projects from the arms 48 a suitable distance and is provided with a ball bearing 60 upon its end, which engages a corresponding socket 61 in the adjacent end of the link 58. A screw plug 62 adapted to fit upon the said ball 60 at its inner end, is put in place in the end of the link 58 so as 125 to complete the bearing engaging the said 130

ball 60. A cotter-pin 63 may then be placed through the end of the link 58 and the said plug 62 to lock the parts in place as clearly shown in Fig. 4. A similar joint is interposed between the end of the link 58 and the arm 57, the said link having a stud 64 projecting therefrom and made with a ball upon the end thereof similar to the ball 60 just described. The socket at the outer end 10 of the link 58 is in all respects like the socket 61 at the other end thereof just described and a cotter pin 65 is employed for holding the retaining plug in the end thereof. The mounting of the parts is thus such 15 that the opening of the throttle valve is always coextensive with the openings of the secondary air inlets and the increase of the gasolene supply. Because of the radial position of the arm 57 when the throttle is 20 closed, the movement imparted to the sleeve 45 will be slow during the first part of its movement, and this corresponds exactly with the action of the throttle valve which at first 25 opens the passage 53.

When the arm 57 nears the end of its stroke and approximates its lowest position it will impart a quicker movement to the sleeve 45 and open the air inlets more rapidly, thus corresponding with the more 30 rapid opening of the passage 53 by the throttle.

The operation of the device will be readily and fully understood from the above description. The lever 56 is connected by a rod 35 or any other suitable means with any operating handle or device within easy reach of the automobile operator or chauffeur. In starting the engine the throttle is practically closed, there being room enough around the 40 edge thereof for a sufficient amount of explosive material to pass to the engine, for starting the same and running it upon low speed. The valve 19 will also permit a like quantity of gasolene to pass into the goose 45 neck passage or carbureting chamber. As soon as it is desired to increase the speed of the engine the lever 56 is pulled upon to slightly open the air passages, the same operation opening the throttle to a slight extent and lifting the valve 19.

As the speed is to be increased the lever 57 is moved farther and farther until the full capacity of the air openings, the throttle and the gasolene inlet passage 14 has been 55 reached. The device is thus positively operated for properly carbureting air for explosive engines and is not subject to the troubles of carbureters which employ automatic air supplies controlled by the suction 60 of the engine.

What I claim is:—

1. A carbureter for explosive engines, comprising a casing provided with a circuitous air inlet passage having a depending portion 65 forming a carbureting chamber; and having

an aperture therein, a fuel feeding mechanism adapted to admit fuel through said aperture, a throttle mechanism, a secondary air feeding mechanism intermediate the inlet passage and the throttle mechanism, and means for simultaneously operating said fuel feeding mechanism and air feeding mechanism for delivering the materials composing the explosive mixture in the proper quantities in proportion to the inflow of air through the air feeding mechanism. 70

2. A carbureter comprising a casing having a mixing chamber formed with an apertured, centrally depressed floor, the said chamber also having openings in its side walls communicating with the atmosphere, the casing also having a circuitous carbureting passage leading from an independent air inlet to the bottom of said mixing chamber, a gasolene supply arranged to enter the lower portion of said passage, a spring controlled valve regulating said supply, an exterior shutter arranged to control the passage of air through the opening in the walls of the mixing chamber, said shutter having a cam path thereon and means carried by the needle valve adapted to engage said cam path for causing the admission of gasolene in accordance with the inflow of air in the mixing chamber. 85

3. A carbureter mechanism comprising a casing having a primary air inlet passage, and a secondary air inlet passage, a gasolene supply arranged for delivering gasolene into said primary inlet passage, the secondary 100 inlet passage having cylindrical walls formed with a series of openings adapted to communicate with the atmosphere, and an apertured wall between it and said primary air inlet passage, a sliding sleeve mounted outside said openings in the cylindrical wall and adapted to control them, connecting means between said sleeve and the throttle mechanism of the engine upon which the carbureter is placed, whereby said sleeve 105 will be moved when the throttle is operated, an adjustable cam spring mounted on said sleeve, a needle valve arranged to control the gasolene supply, means for guiding it in vertical movement, and a roller carried 110 thereby and adapted to engage said cam spring, the structure being such, that when an auxiliary supply of air is introduced through the secondary air inlet passage, a corresponding additional quantity of gasolene will be admitted into and held in the 115 primary air passage. 120

4. A carbureter, comprising a casing having a mixing chamber in open communication with the atmosphere, said casing also 125 having a circuitous carbureting passage leading from a separate primary air inlet to the bottom of said mixing chamber, a gasolene feed supply entering the lower portion of said passage, a valve in said supply, 130

a shutter for controlling the passage of air to the mixing chamber, and means on said shutter coöperating with the valve, whereby the admission of gasolene to the passage is automatically proportioned to the inflow of air to the mixing chamber.

In witness that I claim the foregoing I

have hereunto subscribed my name this 31st day of July, 1911.
